(57) **CLAIM**

The ornamental design for a controller for ionizer, as shown and described.

DESCRIPTION

FIG. 1 is a front, top, and left side perspective view of a controller for ionizer showing the new design.

FIG. 2 is a rear, bottom, and right side perspective view thereof.

FIG. 3 is a front elevational view thereof.

FIG. 4 is a rear elevational view thereof.

FIG. 5 is a top plan view thereof.

FIG. 6 is a bottom plan view thereof.

FIG. 7 is a left side elevational view thereof; and,

FIG. 8 is a right side elevational view thereof.

The broken lines in the drawings depict portions of the controller for ionizer that form no part of the claimed design.
